UNITED STATES PATENT OFFICE.

ERGYES FÖRSTER, OF BUDAPEST, HUNGARY.

PORTABLE BUILDING.

Application filed April 23, 1925, Serial No. 25,202, and in Hungary May 22, 1924.

This invention relates to portable buildings of the knock-down type. More particularly, it relates to a knock-down building that can be readily assembled from structural elements composed of box-framed metal wall sections.

Repeated attempts have been made in the past to construct knock-down houses from metal units manufactured at the factory and transported to the scene of construction as portable building units. Numerous as such attempts have been and simple as such schemes have seemed, actual realization of a successful form of construction is difficult because the finished building must be such as will satisfy the requirements of people of moderate means as regards solidarity, cleanliness, satisfactory heat insulation, and other properties necessary for a substantial house. In addition, of even greater importance is the fact that the manufacture and assembling of such houses should be at such a cost that the entire house can be set up complete more cheaply than can a brick, concrete, or frame building of similar size.

Recognizing the importance of such considerations I have constructed a knock-down type of building composed of structural elements that are made at the factory in the desired form and to the desired dimensions required by the purchaser. Each structural element constitutes a wall section of box-frame construction, and is adapted at its edges to be joined to other sections to provide a complete wall.

The wall sections may be made up of wooden skeleton frames covered on both sides with metal sheathing. The space between the metal sheathing is filled with insulating material such as wood wool, sawdust, excelsior, or the like. The edges of the sections may carry tie bolts or equivalent forms of fastening means for easily connecting the sections together.

The general construction of the sections is such that they can be readily made up at the factory and transported to the point of construction. The thickness of the wall and the dimensions of the various sections depend upon the type and requirements of the building to be set up. In all cases, however, the method of joining the sections together is by means of screw bolts. No nailing or other permanent form of fastening is required.

For a more detailed explanation of my in-

vention reference is made to the following drawings and description wherein two embodiments of the invention are illustrated and described.

Fig. 1 is a sectional view of a wall section on the line 1—1 of Fig. 2.

Fig. 2 is an elevation of one form of wall section including a window opening.

Fig. 3 is an elevation of another form of wall section also including a window opening.

Fig. 4 is a transverse sectional view of the construction shown in Fig. 3.

In the form shown in Figs. 1 and 2, the wooden frame is made up of the uprights 70 and stringers 9 braced by the transverse and longitudinal members 4 and 5. As shown in Fig. 1 the members 9 and 5 constitute the heavy supporting timbers for the frame and the members 4, the bracing members. Over 75 the entire frame is secured the metal sheathing 1 and 2 to form a double walled unit. In the spaces 10 between the frame members and the metal sheathing is stuffed the insulating material 6. For sections designed 80 to include windows, a space 8 is provided and the timbers joined in a manner similar to that shown in Fig. 2. Other sections may be without such spaces and still others may be provided with door space. In all cases 85 the framing is done in accordance with the principles of carpentry involved in such constructions.

Joining of the sections is accomplished by use of the bolts 11 socketed in the side frame members 9. The bolts 11 are of sufficient length to pass through holes 12 provided in the adjacent edges of the adjoining section. Each section is provided on one side with the bolts and on the other with the openings 95 for receiving the bolts of the adjacent section. The sections may be drawn up tight by the usual nuts or other tightening means applied to the bolts.

The embodiment shown in Figs. 3 and 4 100 differs in the frame construction although the general features are still the same. Instead of a frame having heavy uprights and stringers braced by transverse members, Fig. 3 illustrates a frame having heavy 105 stringers and a plurality of lighter weight uprights. The metal sheathing is consequently applied in different fashion as shown in Fig. 4. In this case, the metal is stamped or pressed to fit around a portion of each 110

UNITED STATES PATENT OFFICE.

WOLCOTT C. FOSTER, OF RUTHERFORD, NEW JERSEY, AND ARTHUR S. GARRETT, OF DREXEL HILL, PENNSYLVANIA.

METHOD OF INCREASING THE EFFICIENCY OF ZEOLITES IN THE TREATMENT OF WATER.

No Drawing.

Application filed January 17, 1924. Serial No. 686,934.

Our invention relates to zeolites and particularly to the use of zeolites with raw waters low in alkalinity or acid with free CO_2 .

5 Our main purpose is to provide a way of greatly reducing the deterioration of the zeolite with use in such solutions and thereby materially to increase the length of each run and the number of times the zeolite may 10 be effectively regenerated and used over and over.

A further purpose is to give the raw water a minimum alkalinity before passing it through the beds of zeolite, the degree of 15 alkalinity being preferably sufficient to neutralize any acidity, as from free CO_2 , and further sufficient to maintain the total alkalinity in solution in the raw water to or above a minimum value below which the 20 zeolite deteriorates.

Further purposes will appear in the specification and in the claims.

We have found in practice that the total content of replaceable sodium oxide in the 25 zeolite may be varied and to a certain extent controlled by alkalinity, a zeolite normally tending to take up sodium oxide from solutions strongly alkaline and to give off sodium oxide into solutions of very low 30 alkalinity and that the zeolite deterioration is incident to the tendency to give off sodium oxide, a tendency preventable by increasing the alkalinity.

Thus in a solution of very low alkalinity we have found that there is a distinct tendency for sodium oxide from the zeolite to pass into the solution. This is true whenever the alkalinity of the solution is below a certain minimum value. This is of course intensified if instead of merely low alkalinity the solution be rendered actually acid by the presence of free CO_2 . If the alkalinity be increased or if the acidity be neutralized and the solution be then made alkaline sufficiently, equilibrium is established and wasting of the Na_2O no longer takes place.

Where there is insufficient alkalinity and consequent wastage of Na_2O from the zeolite the remaining zeolite is relatively high in silica and low in Na_2O . We have found this resultant zeolite to be inferior for softening purposes and that the inferiority is more

noticeable the less the amount of Na_2O present.

It is our purpose to maintain alkalinity of 55 the solution treated at or above that which corresponds with this equilibrium value.

Zeolites are substances adapted to base-exchange. They are usually sodium or iron aluminate silicates and are used extensively 60 for softening water for many domestic and technical purposes.

Water softening normally comprises replacing the undesired bases of lime, magnesia, etc., in the water by an alkali base, 65 usually sodium from the zeolite. In the zeolite process the exchange of base takes place in a filter bed of zeolite, loosely bound sodium base of the zeolite filter being exchanged for the undesired bases of the raw 70 water. As the process continues the available base of the zeolite is gradually used up by replacement and the bed loses its effectiveness. After the effectiveness has been reduced to any desired limit the bed is cut 75 out and is regenerated by washing in strong salt solution.

Prior to our invention the process with some waters has been handicapped by wasting and disintegration of the zeolite filter 80 which has lost a considerable portion of its available sodium content without replacement by the hardness bases of the raw water. In this wasting process the zeolite has been permanently injured as a water softener, 85 some of its sodium content passing to solution and the remainder, after the loss of the sodium, loses its hard character and is less suited to base-exchanging and therefore less adapted to water softening and to regeneration. 90

We have found that this wasting has been incident to the treatment of waters low in alkalinity and to waters containing free CO_2 , and that the wasting may in either 95 case be prevented or controlled by the addition of an alkaline base to the raw water. Sodium carbonate and caustic soda give good results.

Our invention lessens disintegration and 100 sludging of the zeolite and (incident to a direct loss of sodium content from the zeolite into the water) a loss of its zeolitic characteristic of base-exchange, the character-

istic which adapts it to water softening and to regeneration.

We have found that where a zeolite bed is fed with water of constitution of the zeolite strongly alkaline the sodium content of the zeolite relatively increases possibly with corresponding decrease in the water content; and that where it is fed with water containing little or no alkalinity in solution there is a decrease in the sodium exchange content, probably with a corresponding initial increase in the amount of water accompanied by wasting of the bed. We have found that there is no material tendency for a bed to lose its sodium exchange power with incidental wasting into the water if the alkalinity of the water is equal to or greater than a fairly low value readily determined by experiment, a value that is a function of the zeolite used.

An obvious advantage of our invention further than stopping wasting of the zeolite is the lengthened life of the beds and the increase in the quantity of water that may be cared for by a given bed before it has to be cut out for regeneration.

In order to facilitate the claiming of our invention and to avoid the necessity for referring to waters low in alkalinity and having acidity in each claim, we shall use the expression "low in alkalinity" in the claims to refer not only to those waters which are alkaline, though having low alkalinity, but to neutral waters and waters rendered acid by free CO_2 as these are obviously "low in alkalinity."

In view of our invention and disclosure, modification and variation in detail to suit individual whim or particular need will doubtless become evident to others skilled in the art and we claim all such broadly in so far as they fall within the reasonable spirit and scope of our invention.

Having thus described our invention, what we claim as new and desire to secure by Letters Patent is:—

1. In water softening, the process of treating raw waters having low initial alkalinity which consists in treating the raw water with a salt which is alkaline in solution until a predetermined standard of alkalinity is reached and in subsequently filtering it through zeolite while the water still has increased alkalinity.

2. In using zeolites in water softening, the process of protecting the zeolite from wasting when used in waters of low alkalinity which consists in adding to the initial alkalinity and in subsequently passing it through the zeolite while it possesses additional alkalinity.

3. In using zeolites in water softening, the process of protecting the zeolite from wasting when used in waters of low alkalinity which consists in continuously adding to the initial alkalinity by a salt of an alkali metal which is alkaline in solution and in subsequently passing it through the zeolite while it possesses added alkalinity.

4. The process of protecting zeolites in the treatment of waters having low alkalinity which consists in increasing the alkalinity to or above a predetermined standard found for a given zeolite and in subsequently passing it through the zeolite while it possesses increased alkalinity.

5. The process of protecting zeolite in the filtration through it of waters having a low alkalinity which consists in increasing the alkalinity until phase equilibrium has been reached between the water and the zeolite with respect to the total metallic oxide equivalent in the zeolite.
